UNITED STATES PATENT OFFICE.

ALVIN MAYER, OF RHINELAND, MISSOURI.

SPARK-PLUG.

1,308,718.

Specification of Letters Patent.

Patented July 1, 1919.

Application filed January 26, 1918. Serial No. 213,944.

To all whom it may concern:

Be it known that I, ALVIN MAYER, a citizen of the United States, residing at Rhine-
land, in the county of Montgomery and State
of Missouri, have invented new and useful
Improvements in Spark-Plugs, of which the
following is a specification.

This invention relates to spark plugs and
it consists in the novel features hereinafter
described and claimed.

An object of the invention is to provide a
spark plug with a contact ball and a cup
shaped socket member which retains the ball
whereby the ball will provide a path for the
passage of current and will obviate any
corners or projections where carbon may accu-
mulate.

A further object of the invention is to
provide in combination with the ball struc-
ture as just stated a point which is pro-
vided at its end with a V-shaped ridge
whereby the current jumps from the ball to
the ridge which will assure the ignition of
the mixture which is presented to the plug.

25 In the accompanying drawing:—

Figure 1 is a vertical longitudinal sectional
view of the spark plug.

Fig. 2 is an end view of the same.

Fig. 3 is a detail sectional view of an end
30 portion of the same.

The spark plug comprises a body 1 of
porcelain or other insulating material
through which a conductor 2 passes. A
socket 3 is carried at the lower end of the

conductor 2, and is provided at its lowest 35
point with an opening 4, and slits leading to
the same. A ball 5 is loosely received in the
socket member 3 and may lie over the opening 4. The relative sizes of the ball and the
socket in the member 3 are such that the ball 40
may freely turn in the socket in consequence
to any shaking or jarring action to which the
spark plug may be subjected. A sleeve 6
surrounds the body 1 and carries at its lower
end a point 7 which is disposed transversely 45
under the socket member 3. The end of the
point 7 is provided with a V-shaped ridge 8
whereby the edge of the said point is rela-
tive sharp.

It is apparent that when the electric cur-
rent is passed from a point to the ball or
vice versa a spark is produced which will
ignite the mixture.

Having described the invention what is
claimed is:—

A spark plug comprising a body, a con-
ductor passing through the body and pro-
vided with a socket member having at its
lowest point an opening, a ball freely mov-
able in the socket member and adapted to 60
close over the opening therein, a sleeve sur-
rounding the body and a point carried by the
sleeve and disposed transversely with relation
to the socket member and below the
same and spaced from the ball and socket 65
member.

In testimony whereof I affix my signature.
ALVIN MAYER.
